INTERNAL COMBUSTION ENGINES
 Salvatore Vitale, % Jack G. Di Prima, 109 Broad St.,
 New York 4, N.Y.
 Filed May 12, 1959, Ser. No. 812,767
 4 Claims. (Cl. 123—56)

This invention relates generally to internal combustion engines, and more particularly to engines operating either as gasoline or diesel engines.

It is known that internal combustion engines operating on the principles of the Otto or the diesel process require characteristic parts for their operation, such as camshafts, cam-controlled intake and exhaust valves with springs, balancing levers, more or less heavy flywheels, etc. Therefore, these engines, also known as four-cycle engines, are relatively complicated in their construction and manufacture, are relatively expensive to produce and require a great deal of maintenance in order to keep them in proper operating condition.

Two-cycle engines also are known, but their method of operation either requires heavy and large engine parts, such as special compressors or scavenger pumps, or leaves certain functions more or less undone resulting in a lesser degree of efficiency.

The present invention contemplates a considerable improvement in these types of internal combustion engines and provides means rendering the possibility of applying the principle of the invention to multi-cylinder power plants.

It is therefore an object of the present invention to provide means contributing to the production of internal combustion engines in a relatively simple and efficacious manner.

It is another object of the present invention to provide means redounding to a highly efficacious construction of internal combustion engines which are relatively simple and utilize a minimum number of operable elements.

It is yet another object of the present invention to provide means devising an improved and highly economical internal combustion engine which operates efficiently and delivers a higher rate of output than heretofore attained.

It is still another object of this invention to provide means envisioning compression of a driving fluid medium to be effectuated in an efficient manner before said medium enters the working cylinders of an internal combustion engine.

It is yet another object of this invention to provide means ensuring stepwise compression of the driving fluid prior to being admitted to the working cylinder of the engine, where it also fulfills the purpose of scavenging burnt or exhaust gases before it is finally compressed in said working cylinder.

Another object of the invention is to provide means conducive to an engine that can be economically produced, can be easily maintained, and has less operating friction engendering elements which could otherwise become a source of disturbances during operation.

Other objects and advantages of the invention will be set forth in part hereinafter and in part will be obvious from the ensuing description or may be learned by practicing the invention, the same being realized and attained by means of the instrumentalities and combinations pointed out in the appended claims.

The invention consists in the novel parts, features, arrangements and combinations of parts as may be shown and described in connection with the engines herein disclosed by way of example only and as illustrative of preferred embodiments.

In the following description and in the claims, parts

2

will be identified by specific terms for convenience, but such terms are intended to be as generic in their application to similar parts as the art will permit. Like reference characters denote like parts in the several figures of the drawings in which:

FIG. 1 is a sectional view of a horizontally arranged four-cylinder engine embodying the invention;

FIG. 2 is a sectional view of a vertically arranged two-cylinder engine;

FIG. 3 is a schematic section of the cylinder combination for one working cylinder according to the invention;

FIG. 4 is a sectional view of a horizontally arranged four-cylinder engine with opposing pistons and arranged in a single block.

Referring now in greater detail to the drawings, there are disclosed in FIG. 1 two blocks or housings 11, 11', each of which comprises as a unit two radially extending working or combustion cylinders 12, 12', two compressor cylinders 13, 13' adjacent said working cylinders 12, 12' and two auxiliary or control cylinders 14, 14' adjacent the compressor cylinders 13, 13'. Slidably supported by and operating in these cylinders are working pistons 15, 15', compression pistons 16, 16' and auxiliary or control pistons 17, 17'.

Extending longitudinally of said blocks or housings is a crank shaft 18 having a corresponding plurality of cranks 19, to which said pistons, 15, 16, 17 and 15', 16', 17' are operatively connected by means of connecting rods 20, 21, 22 and 20', 21', 22'. The working pistons 15, 15' and the compression pistons 16, 16' are connected to the same crank, whereas pistons 16, 16 and 16', 16' are connected to the opposed crank; in other words, on the same side of the opposed-cylinder type of the engine according to the invention, the working piston and the compression piston are 180° opposed to another, whereas the working cylinder on one side and the compression cylinder on the other side of the crankshaft 18 are equally 180° opposed to one another in phase.

All working cylinders in this multi-cylinder engine are operating in synchronism and are fired at the same time. The blocks or housings 11, 11' have water-cooling jackets 23, 23', all moving parts are lubricated in the conventional way.

The blocks or housings 11, 11' are further provided with exhaust ports or outlets 24, 24', arranged in the walls of said blocks and in register with each one of their respective adjacent working cylinders 12, 12' and their pistons 15, 15', thus defining a passageway for removing burnt gases contained in said working cylinders toward the end of the operating or working stroke of said pistons 15, 15'.

On the opposite side of said blocks 11, 11' and in the walls of said auxiliary or control cylinders 14, 14' are intake or inlet ports 25, 25' arranged in such way that said auxiliary or valve pistons 17, 17' may selectively open and close said intake ports in timed relation to the movement of the compressor pistons 16, 16' and working pistons 15, 15'.

Inside the blocks or housings 11, 11' and in the area between the working cylinders 12, 12' and the compression cylinders 13, 13', there are laterally extending channels 26, 26' which communicate with radially extending passageways 27, 27' which terminate in the walls of the working cylinders 12, 12'. Disposed between the auxiliary or valve cylinders 14, 14' and the compressor cylinders 13, 13' are openings or ports 23, 23' which permit the access of the driving fluid received through inlet or intake ports 25, 25' of the auxiliary or valve cylinders 14, 14' to the compressor cylinders 13, 13'.

Thus, it will be clearly apparent, that the driving fluid when contained in said compressor cylinder, will be forced under pressure through channels 26, 26' and

passageways 27, 27' into the working cylinders 12, 12', when the compression pistons 16, 16' are operating on their compression stroke. The timing of the auxiliary or control pistons 17, 17' and the arrangement of the respective openings or ports 25, 25' and 28, 28' is so chosen that a return flow of the driving fluid during and after the compression stroke of the compression pistons is prevented.

The term "driving fluid" has been used as a generic term, and refers to the conventional air-fuel mixture in the case of a gasoline-type engine, and to air in a diesel-type engine. It is further to be understood that the positioning of the inlet or intake ports 25, 25', openings or ports 28, 28' between auxiliary and compressor cylinders, passageways 27, 27' and outlet or exhaust ports 24, 24' are positioned in such way with respect to the movements of the pistons 15, 16, 17 and 15', 16', 17' that they are opened and closed by their cooperating pistons at the proper time during the operation of the engine.

FIG. 2 shows a two-cylinder engine wherein the two operating units comprising a working cylinder 12", a compressor cylinder 13" and an auxiliary cylinder 14" are contained in one block or housing 31. FIG. 3 explains schematically in more detail the operation of the three pistons and cylinders of one operating unit, using the same reference numerals as applied in FIG. 1. FIG. 4 depicts another version of the engine arrangement of FIG. 1, duplicating the arrangement shown in FIG. 2, except for the phase difference of 90° in the crank shaft 18". One half of the cranks 19" are offset by 90° with respect to the other half of the cranks 19", so that the operation of the engine and the output torque of the crankshaft becomes more even and balanced.

Operation

The driving fluid which may be air or an air-fuel mixture, as previously detailed, enters the respective auxiliary cylinders 14, when the auxiliary or control pistons 17 move down towards bottom dead center (BDC) thereby opening inlet or intake port 25. As the auxiliary pistons 17 move toward top dead center (TDC), the adjacent compressor piston 16, slidably supported in said associated compressor cylinder 13, is in position to receive the driving fluid or medium through port 28. As the compressor 16 moves toward top dead center to compress the driving fluid, the working piston 15 in the working cylinder 12 is near bottom dead center, and hence, in position to receive the thus compressed fluid medium at opening 27a through the intermediary of channel means 26 and radial passageways 27 which converge at 27a and are now in their open position.

The working piston 15 thereafter moves towards top dead center, shuts off opening 27a and further compresses the driving fluid contained in the working cylinder 12. When the driving medium is thus compressed, and assuming that said medium is an air-fuel mixture as employed in a gasoline-type engine, the ignition system closes a spark plug circuit (not shown) to produce a spark so that the compressed mixture ignites.

The combustion of said mixture and its resultant expansion, force said working piston towards the bottom dead center thereby imparting rotational movement to the crank shaft 18, while toward the end of its stroke, the exhaust ports 24 are opened in order to clear the burnt gases from the working cylinder. If said engine is operating on the diesel principle, fuel is injected directly into the working cylinder near the end of the compression stroke in a well known manner. This operation occurs in each of the respective auxiliary, compressor and working cylinders in accordance with the rotational movement of the crank shaft 18.

This application is a continuation-in-part application of my co-pending application, Ser. No. 610,184, filed September 17, 1956, now abandoned.

While the invention has been described and illustrated with respect to certain particular preferred examples which give satisfactory results, it will be understood by those skilled in the art after understanding the principle of the invention, that various other changes and modifications may be made without departing from the spirit and scope of the invention and it is intended therefore in the appended claims to cover all such changes and modifications.

Having thus described the invention, what is claimed as new and desired to be secured by Letters Patent is:

- An internal combustion engine comprising a housing having walls defining a power cylinder, a compression cylinder, and a control cylinder, an exhaust port defined at the lower portion of said power cylinder, first conduit means connecting the upper portion of said compression cylinder with the lower portion of said power cylinder, second conduit means connecting the upper portions of said compression and control cylinders together and terminating in a compression port adjacent the top of said control cylinder, an inlet passage terminating in an inlet port defined in the upper portion of said control cylinder below said compression port, a crank shaft rotatably mounted in said housing, power, compression and control pistons connected to said crank shaft and reciprocatable in said power, compression and control cylinders, respectively, said power cylinder being connected to said crank shaft to move downwardly under the force of combustion of a fluid charge in the upper portion of said power cylinder while said compression piston is connected to said crank shaft to move upwardly at the same time and said control piston is connected to be moved to a position adjacent its upper limit of movement and covering said inlet port, said power cylinder being arranged to uncover said exhaust port and said first conduit to discharge exhaust gases and take in a new fluid charge from said compression cylinder, said control piston being movable downwardly in said control cylinder to uncover first said compression port of said second conduit and thereafter said inlet port and thereby communicate said compression cylinder with the upper portion of said control cylinder and with said inlet port as said compression piston is moved downwardly in said compression cylinder, said control piston being movable upwardly to first cover said inlet port and thereafter said compression port.

- An internal combustion engine according to claim 1, wherein said housing includes a separate second power, compression and control cylinder and piston disposed substantially 180° away from said first set, said power, compression and control piston of said second set being connected to said crank at 180° out of phase from the respective power, compression and control cylinders of said first set.

- An internal combustion engine according to claim 1, wherein said control piston is a solid piston.

- An internal combustion engine according to claim 1, wherein said housing means includes a second set of power, compression and control cylinders defined substantially in alignment with said first set and including second power, compression and control pistons reciprocatable in said respective second power, compression and control cylinders and connected to said crank case for operation of respective pistons in phase.
